THERMIONIC TUBE

Felix L. Yerzley, Ithaca, N. Y., assignor to Radio Corporation of America, New York, N. Y., a corporation of Delaware

Application August 3, 1934, Serial No. 738,265

2 Claims. (Cl. 250—27)

My invention relates to thermionic tubes and has particular reference to tubes employing heated surfaces for maintaining a current of electrons.

5 Thermionic tubes, for example those used as detectors and amplifiers in radio circuits, must maintain a very uniform rate of emission of electrons. Any variations in the rate of emission become immediately apparent in the output 10 of the tube. When sufficiently amplified, they manifest themselves, for instance, as noise in a receiving circuit. With uneven electron emission the noise amplitude may be great enough to mask the incoming signals completely.

15 An ideal vacuum tube, therefore, must be completely free from such fluctuations in order to maintain maximum possible sensitivity of tube circuits.

Extensive experience with the thermionic tubes 20 has demonstrated, however, that it is extremely difficult to obtain a perfectly uniform flow of electrons. Unlike a flowing liquid, the stream of electrons consists of finite particles, each having a discrete electrical charge, and the rate of emission of these particles is not constant. Thus, although the average current is reasonably the same 25 over a period of time, instantaneous values of the emission current vary slightly from this mean. This statistical fluctuation represents one of the 30 major problems in the development of thermionic tubes. It is well known as the "shot effect", so named by W. Schottky who first predicted it in 1918.

A large part of these fluctuations can be removed by the use of a space charge over the emitting surface of the filament. The space charge 35 is formed by adjusting relative potentials of the plate and filament to a point where the mutual repulsion of the electrons begins to take effect in retarding their movement and causing thereby a certain accumulation or cloud of free electrons 40 near the emitting surface of the filament. This cloud or space charge serves as a reservoir absorbing the statistical fluctuations, and its outer 45 boundary serves as a fairly uniform emitter.

The accumulation of electrons forming a space charge alters, however, the potential distribution 50 between the filament and the plate. The high density of electrons near the emitter is sufficient to lower the potential even below that of the emitting surface. Such lowering of potential introduces a new and very undesirable effect by causing the attraction of positive ions which are also emitted by the filament.

55 Experience with electron emitting bodies has

shown that together with the electrons there is always some emission of positive ions. The mobility of ions and electrons is such that an ion may exist for a long time in the electron space charge before it is neutralized by combination 5 with an electron. During the time it is present in space charge region the potential there is somewhat higher and many more electrons reach the plate than is normal. From theoretical considerations it has been shown that a single positive 10 ion in a space charge of electrons may release hundreds, and under certain conditions thousands, of electrons. Positive ions, then, may be responsible for great variations in the plate current, and are therefore extremely detrimental to 15 the proper operation of thermionic tubes. In the case of radio tubes the disturbance due to positive ions results in a high "noise level".

I discovered, however, that it is possible to eliminate almost completely the effect of the positive 20 ions on the plate current. My research has shown that for a straight filament the positive ion emission is limited almost entirely to its cooler portions. I found that by placing conductors near 25 these cooler portions of the filament and applying to them a negative potential it is possible to collect the positive ions thereby largely eliminating 30 their effect on the flow of electrons.

My invention is more fully described in the accompanying specification and drawing in which—

Fig. 1 is a diagrammatic view of a thermionic tube employing my positive ion collectors, Fig. 2 is a diagrammatic view of a tube without my 35 collectors, Fig. 3 is a curve showing temperature distribution along the filament of a tube, Fig. 4 is a curve showing the rate of electron and positive ion emission from the filament, and Figs. 5 and 6 are diagrammatic views of another arrangement of a filament with my collectors.

The findings of my research are that for a 40 straight filament 1, supported by lead wires 2, the positive ion emission is limited almost entirely to the end portions of the filament (or a similar ion emitting element) where there is a steep temperature gradient. This may be explained by the fact that the cooler portions of the 45 filament retain most of the impurities originally present in the wire, and these impurities, form the principal cause of the positive ion emission. Of course, a certain amount of the impurities 50 originally present always remain in the central portion, and it seems difficult to reconcile this fact with the almost total lack of positive ion emission from the central portion. A possible explanation is that in the central region the im- 55

purities leave the surface as neutral atoms or as negative ions.

The intensity of the electron emission is a function of the temperature of the filament. For a hot filament the temperature distribution along the filament may be represented approximately by the curve 3 in Fig. 3, while the electron emission may be represented by a curve 4, Fig. 4. In the latter figure abscissa on this curve represents points on the length of the filament, and the ordinates represent the positive ion emission and the intensity of the electron emission, the latter decreasing rapidly near the ends of the filament due to the cooling effect of the supporting wires. The positive ion emission is represented in Fig. 4 by curves 5 corresponding to the cooler portions of the filament. Such conditions of the electron and ion emission exist in an ordinary tube, such as a triode illustrated diagrammatically in Fig. 2. Here the filament 1 is surrounded by a grid 6 connected with a grid circuit 7. The grid is surrounded by a plate 8 connected with a plate circuit 7' through a source of electric current 9. In my tube as shown in Figs. 1 and 3, I use the same principal elements, but I add shields or electrodes 10 surrounding the cooler portions of the filament. These shields are given a negative potential from a source of current 11. The potential must be so adjusted that the shields will attract and remove the positive ions emitted by the end portions of the filament. The grid and the plate may be correspondingly shortened so as to surround the active portions only of the filament not protected by my shields or ion collectors. Such shortening of the usual elements of the tube will not materially affect its output, as it removes only comparatively inactive portions corresponding to the zones of low electron emission on the filament. With this arrangement my shields do not in any way interfere with the normal operation of the tube. This follows from the fact that the operation of a thermionic tube depends upon the distribution of potential between the plate and the filament, and not upon the potential distribution in other parts of the tube. There would be no disturbance caused even were it found necessary in a special case to place the positive ion collectors over part of the surface emitting electrons in large numbers, or if there is some overlapping of the usual tube elements and my ion collectors. In general, however, my researches pointed out that the collectors fulfil their purpose satisfactorily when they are placed only over regions where the electron emission is negligible.

The positioning and size of my collectors vary depending on the emitting properties of the filament, whether it is a pure metallic filament, an oxide coated filament, a thoriated filament, or some other type. It depends also on the temperature gradient and the potential applied, i. e., the

consequent distribution of the electron space charge.

My collectors need not form a part of any of the ordinary tube circuits. They form an essential part of a "bleeder circuit" provided for removing an undesirable component of the total emission without appreciably altering other conditions of the tube. 5

My collectors are especially effective with tubes employing coated filaments and for tubes using heater cathodes. These operate at relatively low temperatures and are especially capable of emitting positive ions in the manner indicated. 10

For filaments other than a single straight length of fine wire, such as hairpin types, or inverted W types, there are more than two short lengths of filament which emit positive ions in large quantities. In all such cases, however, it is possible to provide my collectors over the cooler portions of the filament, as shown, for instance, 15 in Figs. 5 and 6. In Fig. 5 there is illustrated a straight filament 12 attached to the supports 15 and 16, the latter or both of which may be lead-in wires. The shields 13 and 14 serve to protect the filament at its points of support. In Fig. 6 a W 20 25 filament 12' is protected by shields 13' and 14' near its points of support 15' and lead wires 16'. 25

Example.—A 4.8 mil tungsten wire filament 7 cm. long was found to require positive ion collectors 5 millimeters long at each end of the filament. A negative potential of 30 volts was found to be satisfactory relative to the filament. This arrangement leaves, therefore, 85% of the length of the filament to be surrounded by the usual grid and plate, utilizing, however, over 99.5% of the 30 35 total electron emission.

It should be noted that my positive ion collectors are applicable to all tubes employing heated surfaces for the electron emission and not employing a gas discharge. The addition of my collectors to tubes does not call for any fundamental alterations in diodes, triodes, tetrodes, pentodes, or any other of the multiplicity of tubes now in use or in the process of development. 40

I claim as my invention:

1. A thermionic system comprising in combination a tube provided with grid and anode electrodes, and an electron emitting member, means for supporting said emitting member, means for heating said emitting member, the portions of which adjacent points of support are cooler than other portions of the member, shields surrounding the cooler portions of the member adjacent its points of support, and means to maintain the shields at a negative potential with respect to the emitting member, said shields being located substantially parallel to said member and nearer thereto than the anode. 45 50 55

2. A thermionic system as defined in claim 1, wherein the shields are electrically connected together. 60
